UNITED STATES PATENT OFFICE.

RUSSELL H. WILHELM, OF EASTON, PENNSYLVANIA, ASSIGNOR TO INGERSOLL-RAND COMPANY, OF JERSEY CITY, NEW JERSEY, A CORPORATION OF NEW JERSEY.

SPIKE-HOLDING DEVICE.

Application filed December 24, 1924. Serial No. 757,824.

To all whom it may concern:

Be it known that I, RUSSELL H. WILHELM, a citizen of the United States, and a resident of Easton, county of Northampton, State of Pennsylvania, have invented a certain Spike-Holding Device, of which the following is a specification accompanied by drawings.

This invention relates to improvements in railroad spiking devices, but more particularly to a device for holding and guiding the spike while it is being driven into the tie. The present invention is especially adapted to be used in conjunction with a pneumatic spike driver or other similar tools.

One object of the invention is to enable the spike to be held and guided by mechanical means during the initial driving of the spike.

20 Another object is to separate the spike supporting members automatically after the initial driving of the spike to permit the driving element and the head of the spike to pass therebetween.

25 Further objects will appear hereinafter. In the drawings forming part of this specification,

Figure 1 is a side elevation of a spike holding device showing the normal position 30 of the parts;

Figure 2 is a view similar to Figure 1 showing the holding members separated by the end of a pneumatic spike driver,

Figure 3 is an end elevation of the device, 35 and

Figure 4 is a top plan view.

Referring to the drawings, the spike holder comprises a saddle member A having a base B, a depending flange C on one side, 40 and depending guide plates D on the opposite side. In this instance the base B is adapted to lie directly on the top surface of a rail E. Suitable lugs F are arranged to contact with one side of the rail, and with 45 the flange C form a guide-way for sliding the device along the head of the rail, and to prevent transverse movement of the device.

The guide plates D are preferably formed with an angular base G to register with the 50 edge of the rail flange and to be supported on the top face of the flange, thereby holding the device in operative position.

Means are provided for holding and guiding a spike H until it has penetrated the tie H' to a suitable depth when mechanical

guidance is no longer required. To this end, a pair of arms J having recessed jaws K at one end are mounted on transverse pivots L, and are provided with lateral lugs O to cooperate with the top of the base B 60 for limiting the movement of the arms in one direction.

The jaws K are preferably held in clamping position by plungers P and coil springs Q, which act upon one side of the arms to 65 force the jaws toward a common central position. Grip members R are arranged near the ends of the base B, thus providing convenient means for transferring the device from one position to another. 70

In this instance the forward portion of a pneumatic spike driver S is shown in operative position on the head of the spike H.

In operation, the device is arranged upon the rail directly over the tie. The spike is 75 then inserted between the jaws K, and the driver S is applied to the head of the spike. As the spike penetrates the tie, the front end of the driver will act upon or against the top surface of the jaws K thereby causing the jaws to rock simultaneously about the pivots L and permit the forward end of the driver S to pass therebetween.

Upon removal of the driver, the jaws will be returned automatically to their normal 85 position by the plungers P and the spring Q. The device may then be placed in position to drive a spike on the opposite side of the rail, as indicated by the broken lines in Figure 3, or may be moved slidably along 90 the rail to the next tie.

Although the invention is described as having only a single pair of jaws, it is to be understood that a similar pair may be arranged on the opposite side of the device. 95 In this manner spikes may be driven into the tie on the opposite sides of the rail without requiring a change in the position of the device.

I claim:

1. In a spike holding device, a saddle member having a base, a depending flange, depending guide plates, arms mounted pivotally on the saddle having jaws to hold a spike, and means for holding the jaws in a 105 normally closed position.

2. In a spike holding device, a saddle member having a base, a depending flange, depending guide plates, pivotally mounted arms with jaws for supporting a spike per- 110

pendicularly to a working face, and means for holding the jaws yieldingly against the spike.

3. In a spike holding device, a saddle member having a base, a depending flange, a pair of depending guide plates, pivotally mounted arms having jaws at one end to support and guide a spike and lugs at another end to limit the movement of the arms in one direction, and resilient means for holding the jaws yieldingly against the spike.

4. In a spike holding device, a saddle member having a base, a depending flange, depending guide plates, a pair of arms having recessed jaws at one end and lateral lugs at another end and secured pivotally to the saddle to slidably support a spike perpendicularly to a working face, and spring

pressed plungers to force the jaws against the spike. 20

5. In a spike holding device, a saddle comprising a base, a depending flange to cooperate with a side of the rail and a pair of depending guide plates to cooperate with a rail-flange for supporting the device in an operative position upon the rail, a pair of arms mounted pivotally to one face of the saddle, said arms having recessed jaws at one end to receive and guide a spike 25 and lugs at another end to limit the movement of the arms in one direction, and spring pressed plungers co-acting against the arms to return the jaws to a normally closed position. 30

In testimony whereof I have signed this specification.

RUSSELL H. WILHELM.
